CLAIM

The ornamental design for a glove, substantially as shown and described.

DESCRIPTION

FIG. 1 is a perspective view of a right-handed glove which embodies the new design;

FIG. 2 is a plan palm view of a right-handed glove embodying the new design;

FIG. 3 is a plan dorsal view of a right-handed glove embodying the new design;

FIG. 4 is a side view of a right-handed glove, when viewed with the little finger closest to the viewer, embodying the new design;

FIG. 5 is a side view of a right-handed glove, when viewed with the thumb closest to the viewer, embodying the new design;

FIG. 6 is a top view of a right-handed glove embodying the new design; and,

FIG. 7 is a dorsal perspective view of a right-handed glove embodying the new design.

FIGS. 1-7 illustrate a right-handed glove design of the present invention, it is to be understood that the invention includes a left-handed glove design, the views for which would be illustrated as mirror images of any or all of the views shown in FIGS. 1-7.

The broken lines in the figures depict portions of the glove and form no part of the claimed design.

1 Claim, 7 Drawing Sheets
